UNITED STATES PATENT OFFICE.

ERASTUS E. WINKLEY AND BENJAMIN PHILLIPS, OF LYNN, MASSACHUSETTS.

BUFFING-MACHINE.

SPECIFICATION forming part of Letters Patent No. 748,677, dated January 5, 1904.

Application filed February 3, 1902. Serial No. 92,267. (No model.)

To all whom it may concern:

Be it known that we, ERASTUS E. WINKLEY and BENJAMIN PHILLIPS, citizens of the United States, residing at Lynn, in the county of Essex and State of Massachusetts, have invented certain new and useful Improvements in Buffing-Machines; and we do hereby declare the following to be a full, clear, and exact description of the invention, such as will enable others skilled in the art to which it appertains to make and use the same.

The present invention relates to buffing-machines.

In the manufacture of boots and shoes it is customary to clean the bottoms of the soles in order to provide a clean smooth surface suitable for receiving the dressing and for being polished. This has heretofore been done by means of buffing-machines which comprise a suitable buffing device, such as a roller or pad, against which the shoe is held by the operator, the shoe being pressed backward and forward beneath the buffing roller or pad and tilted in various directions in order to bring all portions of the sole to be cleaned in contact therewith.

The object of the present invention is to provide an automatic buffing-machine by which the soles of shoes may be cleaned without any manipulation of the shoes by the operator except the placing of the shoes upon a shoe-supporting jack and the removal of them therefrom after the buffing operation has been completed.

With this object in view our invention consists in a buffing-machine provided with a suitable buffing device, means for actuating the same, a shoe-supporting jack, and means for relatively actuating the buffing device and jack to transfer the point of contact of the buffing device over the sole of a shoe supported upon the jack.

Our invention also consists in a buffing-machine provided with a buffing device and a shoe-supporting jack which are relatively actuated to transfer the point of contact of the buffing device over the sole of a shoe supported upon the jack and with means for changing the relative inclination of the jack and buffing device during the buffing operation in order to cause the buffing device to act

properly upon the irregular curved surface of the sole.

Our invention also consists in certain devices and in certain constructions, arrangements, and combinations of parts which will be hereinafter described and claimed, the advantages of which will be obvious to those skilled in the art.

While our invention, broadly considered, 60 contemplates the use of any suitable form of buffing device—such, for instance, as a buffing-roller—we prefer to use a rotary buffing-pad, as the working surface of such a pad is substantially flat and bears upon a considerable 65 area of the bottom of the sole at all times during the buffing operation, so that any liability of certain portions of the sole being cut away more than other portions is avoided and a smooth and even surface is produced, which 70 result cannot be accomplished with certainty when a buffing-roller is employed, as the roller contacts with the surface of the sole at a single line or point and is liable to cut away the sole more at some places than at others, especially when there are inequalities in the 75 density of the stock. The soles of shoes are usually subjected to the buffing operation after the heels have been attached, and a further advantage gained by the use of a rotary 80 buffing-pad is that by means of such a pad the shank portion of the sole close to the breast of the heel can be cleaned as well as the other portions of the sole, which result cannot be accomplished by the use of a buff- 85 ing-roll, as will be evident.

In embodying our invention in the best form at present known to us we secure the relative movement of the jack and buffing device to transfer the point of contact of the 90 buffing device over the sole of the shoe by moving the jack back and forth beneath the buffing device, and we produce the change in the relative inclination of the buffing device and jack to cause the buffing device to act 95 properly upon the surface of the sole by tipping the buffing device in directions extending laterally and longitudinally of the shoe supported upon the jack.

As we have stated, the buffing operation is 100 usually performed upon the shoe after the heel has been attached thereto, and we have

accordingly provided means whereby the jack may be adjusted to cause the breast of the heel, the position of which varies in different sizes and styles of shoes, to be brought into close proximity to the buffing device during the movement of the jack, such means in the preferred embodiment of our invention, hereinafter specifically described, consisting of means for adjusting the mechanism for actuating the jack.

In order to enable the shoes to be readily placed upon the jack and to be removed therefrom after the buffing operation, we have mounted the jack so as to be movable from a position in which the shoes can be readily placed thereon and removed therefrom, which position we term a "position of presentation," to a position in which the sole of the shoe can be acted upon by the buffing device, and we have provided means for connecting the jack to its actuating mechanism after having been so moved. To allow the jack to return to its position of presentation, we have provided means for automatically disconnecting the jack from its actuating mechanism at the end of the buffing operation, which means are preferably arranged to act when the toe portion of the shoe supported on the jack is in proximity to the buffing device. The means for connecting the jack to its actuating mechanism and for disconnecting it therefrom not only allows the jack to move from its operative position to a position in which the shoe can be readily removed therefrom, but also enables a number of jacks and coöperating buffing devices to be used in the same machine, whereby one jack can be connected to its actuating mechanism while the other jack is in a position of presentation, as will hereinafter be more fully explained. Since the position of the breast of the heel varies with the style or size of shoe being operated upon, we prefer to move the jack from its position of presentation to a position in which the shank portion of the sole close to the breast of the heel is beneath the buffing device and to connect the jack to its actuating mechanism when in such position, the adjusting means of the jack-actuating mechanism allowing the jack to be adjusted after being so connected to bring the breast of the heel in close proximity to the buffing device. To allow the jack to be so moved, we have provided means for raising the buffing device above the level of the sole of the shoe after the jack has been disconnected from its actuating mechanism and for holding it in its raised position until the jack is again connected to its actuating mechanism. Certain of the features of construction and operation above referred to are equally applicable to other forms of machines for operating upon the soles of shoes—such, for instance, as sole-leveling machines of the vibrating-roll type—and as to these features we do not consider our invention as limited to a sole-buffing machine, sole-leveling machines,

or other machines for operating upon the soles of shoes embodying these features of construction, being equally within the purview thereof. Thus we believe that we are the first to provide any form of machine for operating upon the soles of shoes with a jack which is movable from a position of presentation to a position in which the sole of the shoe supported thereon is beneath the device for acting upon the sole of the shoe and with means for connecting the jack to its actuating mechanism when in such position. We also believe that we are the first to provide any form of machine for acting upon the soles of shoes with means for connecting the jack to its actuating mechanism when the jack is in a position in which the shank portion of the sole of the shoe is beneath the device for acting upon the sole and with means for disconnecting the jack from its actuating mechanism when the toe of the shoe is in proximity to the device for acting upon the sole of the shoe. We also believe that we are the first to provide any form of machine for operating upon the soles of shoes with means for holding the device for acting upon the soles of shoes above the level of the sole while the jack is being moved into a position beneath the device. We desire, therefore, to be understood as claiming these features of construction and operation whether embodied in a buffing-machine or in other forms of machines for operating upon the soles of shoes.

A buffing-machine embodying our invention in its preferred form is illustrated in the accompanying drawings, in which—

Figure 1 is a view in side elevation thereof. Fig. 2 is a sectional plan view of the machine, taken on the line 2-2 of Fig. 1. Fig. 3 is a detail plan view illustrating the mechanism for supporting and actuating the buffing device, and Fig. 4 is a detail view illustrating a portion of the mechanism for imparting lateral tipping movements to the buffing device.

Referring to the drawings, in which like characters of reference indicate like parts in the several views, 1 indicates the frame of the machine, and 2 a shaft journaled therein, to which are secured the several cams from which the moving parts of the machine are operated, as will be hereinafter described.

3 indicates the shoe-supporting jack, which may be of any suitable construction for supporting a shoe and presenting the sole of the shoe to the buffing device, the jack shown being constructed to support an ordinary wooden last. To this end it is provided with a toe-support 4 and with a heel-support 5, the upper end of which is provided with a last-pin (not shown) to enter the usual hole in the last. The jack is provided with a hub 6, which is loosely mounted upon a shaft 7, extending across the front portion of the machine-frame parallel with the cam-shaft 2. The jack is capable of an oscillating movement about the shaft 7 as a pivot in a direc-

tion which extends longitudinally of the shoe supported upon the jack and is so oscillated to move the shoe back and forth beneath the buffing device by mechanism which may be described as follows: Secured to the shaft 7 or mounted loosely thereon is the sleeve 8 of a downwardly-projecting arm 9, which is provided with an arc-shaped slot 10. A block 11, provided with a portion which projects into and fits the slot 10 and with a flange projecting over the edge of the arm, is secured to the arm by means of a set-screw 12, which has a screw-threaded engagement with the flange and bears against the edge of the arm. This block is pivotally connected to one end of a link 13, the other end of which is pivotally connected to a lever 14, pivoted to the frame of the machine and provided at its free end with a roll or stud which engages a cam-groove 15 in the face of a cam-disk 16, secured to the shaft 2.

The above-described construction is such that oscillating movements are imparted to the arm 9 during the revolution of the shaft 2, the extent of which oscillating movements can be varied by adjusting the block 11 on the arm 9 for a purpose which will be hereinafter explained.

The arm 9 is provided with a horizontally-extending portion, upon which is pivotally mounted a spring-pressed pawl 17. (See more particularly Fig. 2.) This pawl is adapted to engage a slot or notch formed in an arm 18, projecting rearwardly from the hub 6 of the jack 3 when the jack is moved into a position to bring the slot in the arm 18 opposite the pawl. When the arm 18 is engaged by the pawl 17, the jack is rigidly connected to the arm 9 and the oscillating movements of the arm are imparted to the jack.

The buffing device is indicated at 19 and, as shown, consists of a rotary pad, the advantages of which over other forms of buffing devices have heretofore been explained. The oscillating movements imparted to the jack transfer the point of contact of the buffing-pad back and forth over the sole of a shoe supported upon the jack in a direction extending longitudinally of the shoe. In order to cause the buffing-pad to act properly upon the irregular curved surface of the sole of the shoe during the oscillating movements of the jack, it is supported and actuated as follows: The buffing-pad is secured to the lower end of a shaft 20, journaled in bearings in a frame 21, pivotally mounted between the arms of a yoke-shaped frame 22. The frame 22 is secured to a shaft 23, journaled in a frame 24, pivotally mounted upon the upper rear portion of the main frame of the machine. The buffing-pad is thus supported so as to be capable of a tipping movement in a direction extending longitudinally of the shoe supported upon the jack, of a tipping movement extending laterally of the shoe supported upon the jack, and of a movement toward and from the surface of the sole, the longitudinal

tipping movement being allowed by the pivotal connection between the frames 21 and 22, the lateral tipping movement of the pivotal connection between the frames 22 and 24, formed by the shaft 23, and the movement toward and from the surface of the sole by the pivotal connection between the frame 24 and the main frame of the machine. The frame 21 is oscillated during the operation of the machine to produce a longitudinal tipping movement of the buffing-pad by means of a link 25, one end of which is connected to a projection 26 on the frame 21 and the other end of which is connected to an arm extending upwardly from a block 27, loosely mounted upon the rear end of the shaft 23. The block 27 is provided with a groove which is engaged by pins projecting inwardly from the forked upper end of a lever 28, the lower end of which is connected by a link 29 to the upper end of a lever 30, the lower end of which is provided with a roll or stud which engages a cam-groove 31 in one of the faces of the cam-disk 16. The link 29 is adjustably connected to the lower end of the lever 28, as shown in Fig. 1, whereby the extent of the longitudinal tipping movements imparted to the pad can be varied, if desired. The mechanism for oscillating the frame 24 to tip the buffing-pad in a direction extending transversely to the shoe supported upon the jack consists of a segmental gear 32, a pivotally-mounted toothed segment 33, meshing therewith, (see more particularly Fig. 4,) a lever 34, provided with a stud or roll bearing upon a cam-disk 35, secured to the shaft 2, a link 36, connecting the free end of the lever 34 with the segment 33, and a coiled spring 37, arranged to act on the lever 34 and hold the roller or stud carried thereby in contact with the cam 35.

A grooved pulley 38 is mounted to rotate freely on the shaft 23 and is continuously rotated from any suitable source of power by a belt (not shown) passing over the pulley. A belt 39 passes over the pulley 38, over two guide-pulleys 40, mounted upon an arm projecting from the segmental gear 32, and over the pulley 41, mounted concentrically with the pivot of frame 21. A belt 42 also passes over the pulley 41, over two guiding-pulleys 43, mounted upon the frame 21, and over a pulley 44 upon the upper end of the shaft 20, to which the buffing-pad is secured. The buffing-pad is thus rotated continuously from the pulley 38 through connections which allow the frames 21 and 22 to be oscillated, as above described. In the construction shown in the drawings it will be seen that the axes about which the frames 21 and 22 are oscillated are always located in substantially the same plane as the working surface of the pad, so that the tipping movements of the pad merely change the relative inclination of the pad and jack, but do not otherwise change the position of the pad with relation to the jack.

During the buffing operation and while the jack is connected to its actuating mechanism the buffing-pad is held in contact with the surface of the sole by the weight of the various parts supported from the frame 24. After the buffing operation has been completed, however, and after the jack has been disconnected from its actuating mechanism the frame 24 is actuated to raise the buffing-pad 10 above the level of the sole of the shoe supported upon the jack and is held in such position until the jack is again connected to its actuating mechanism. For so actuating the frame 24 a projection 45 is provided on the 15 circumference of the cam-disk 16, which is arranged to engage an arm 46, projecting downwardly from the frame 24. The cam-disk 16 is also provided with a lateral projection 47, which is arranged to engage an 20 arm 48, secured to or formed integral with the pawl 17, at the proper time during the operation of the machine and move said pawl out of engagement with the arm 18, and thereby disconnect the jack from its actuating 25 mechanism. When the jack is disconnected from its actuating mechanism, it falls backward against a fixed stop 49 into a position to allow the shoe which has been operated upon to be removed and another shoe to 30 be placed thereon.

The cam-shaft 2 is rotated by means of a worm 50, which meshes with a worm-gear 51, secured to the shaft 2, the worm 50 being secured to a shaft 52, journaled in the lower 35 portion of the machine-frame at right angles to the cam-shaft. A driving-pulley 53 is mounted to rotate loosely upon the shaft 52 and to be capable of a longitudinal movement on the shaft, and a clutch member 54 40 is secured to the shaft in a position to be engaged by a clutch member 55, secured to the pulley, when the pulley is moved on the shaft longitudinally in one direction and to be disengaged therefrom when the pulley is moved 45 in the opposite direction. The pulley 53 is rotated by means of a belt 56, passing over the pulley and over a pulley 57, secured to a shaft 58, journaled in the upper portion of the machine-frame. The shaft 58 is driven 50 from any suitable source of power by means of a belt, which also passes over the pulley 57.

As a means for throwing the machine into and out of operation a rock-shaft 59 is mounted in the lower portion of the machine-frame 55 parallel with the shaft 52, upon which is loosely mounted an arm 60, which engages a groove formed in the clutch member 55, secured to the pulley 53. An arm 61 is secured to the shaft 59 and extends into the path of 60 movement of a projection 62 on the worm-gear 51. A coiled spring 63 surrounds the shaft 59 and is connected at one end to the frame of the machine and at the other end to the shaft 59 or to the arm 61, the tendency 65 of which spring is to rotate the shaft 59 in a direction to bring the arm 61 into the path of movement of the projection 62 and to move

the shaft 59 longitudinally in a direction to bring the clutch members 55 and 54 into engagement. A treadle 64, secured to the shaft 70 59, serves as a means for rotating the shaft against the tension of spring 63 to remove the arm 61 from the path of movement of the projection 62.

Briefly described, the operation of the machine is as follows: When the machine is at rest, the projection 62 is pressed against the arm 61 and the shaft 59 is moved to the left, as viewed in Fig. 1, and the clutch members 54 and 55 are disconnected. Also the jack is 80 disconnected from its actuating mechanism and is in its position of presentation resting against the stop 49. A shoe having been placed in position upon the jack, the jack is moved toward the buffing-pad, which is held 85 raised above the level of the sole of the shoe by the engagement of the projection 45 of the cam-disk 16 with the lower end of the arm 46 to allow the shoe to pass beneath the pad. The jack is moved until the shank portion of 90 the sole of the shoe is in proximity to the breast of the heel is beneath the buffing-pad, in which position of the jack the arm 18 is opposite the pawl 17, which engages the arm and connects the jack to its actuating mechanism. If necessary, the block 11 is now adjusted on the arm 9 until the breast of the heel is brought close to the edge of the buffing-pad, the shape of the slot 10 in the arm 9 and the position of the arm being such that 100 the arm, and consequently the jack, is moved by the adjustment of the block 11. The adjustment of the block 11 also changes the extent of the oscillating movements imparted to the jack, so that the extent of such movements corresponds to the distance from the breast of the heel to the toe of the shoe supported upon the jack. When, therefore, the breast of the heel has been brought close to the edge of the buffing-pad, the machine has 110 been adjusted for operation upon the particular shoe which has been placed on the jack. The jack-actuating mechanism having been properly adjusted, the operator presses upon the treadle 64, and thereby rocks the 115 shaft 59 to remove the arm 61 from the path of movement of the projection 62, and the spring 63 moves the shaft 59 longitudinally to bring the clutch members 54 and 55 into engagement. During the rotation of the cam-shaft 2 the buffing-pad is allowed to descend 120 into contact with the sole by the removal of the projection 45 from beneath the arm 46, and the jack is moved to transfer the point of contact of the buffing-pad from the breast 125 of the heel to the toe portion of the shoe, then from the toe portion of the shoe back to the breast of the heel, and then again from the breast of the heel to the toe portion of the shoe, at which time in the operation of the 130 machine the parts are in the position illustrated in Fig. 1. During the backward and forward movements of the jack beneath the buffing-pad the pad is tipped longitudinally

and laterally to cause the pad to act upon all portions of the sole of a shoe, as has been described. The continued rotation of the shaft 2 in the direction indicated by the arrow in Fig. 1 brings the projection 47 in contact with the arm 48 of the pawl 17 and moves the pawl out of engagement with the arm 18. The jack being now disconnected from its actuating mechanism falls backward from the buffing-pad and rests against the stop 49. The cam-shaft continues to rotate until the projection 45 is brought into contact with the arm 46 and actuates the arm to raise the buffing-pad, and the projection 62 of the gear 51 contacts with the arm 61 and moves the shaft 59 in a direction to disengage the clutch members 54 and 55.

It will be evident that if the cam-shaft 2 is rotated while the jack is disconnected from its actuating mechanism the jack will not be actuated, but will remain in its position of presentation in contact with the stop 49 and that, if desired, a second jack, together with a coöperating buffing device, might be provided, which second jack could be connected to the jack-actuating mechanism and moved back and forth beneath its coöperating buffing device while the other jack was in its position of presentation, whereby the machine could be operated continuously, or substantially so, in the same manner as certain well-known sole-leveling machines.

Having thus indicated the nature and scope of our invention and having specifically described a machine embodying the same in its preferred form, we claim as new and desire to secure by Letters Patent—

1. A buffing-machine, having, in combination, a shoe-supporting jack, a buffing device, means for actuating the buffing device, and mechanism for actuating the jack to transfer the point of contact of the buffing device back and forth over the sole of a shoe supported upon the jack, substantially as described.

45 2. A buffing-machine, having, in combination, a shoe-supporting jack, a buffing device, means for actuating the buffing device, and connected mechanism acting automatically to actuate the jack to transfer the point of contact of the buffing device back and forth over the sole of a shoe supported upon the jack and to relatively actuate the buffing device and jack to change their relative lateral inclination, substantially as described.

55 3. A buffing-machine, having, in combination, a shoe-supporting jack, a buffing device, means for actuating the buffing device, and connected mechanism acting automatically to relatively actuate the buffing device and jack to transfer the point of contact of the buffing device over the sole of a shoe supported upon the jack, and to change the relative longitudinal inclination of the buffing device and jack, substantially as described.

65 4. A buffing-machine, having, in combination, a shoe-supporting jack, a buffing device, means for actuating the buffing device, and

connected mechanism acting automatically to relatively actuate the buffing device and jack to transfer the point of contact of the buffing device over the sole of a shoe supported upon the jack and to change the relative lateral and longitudinal inclination of the buffing device and jack, substantially as described. 70

5. A buffing-machine, having, in combination, a shoe-supporting jack, a buffing-pad provided with a substantially flat working surface, means for rotating the pad, and mechanism for relatively actuating the pad and jack to transfer the point of contact of the pad over the sole of a shoe supported upon the jack, substantially as described. 75

6. A buffing-machine, having, in combination, a shoe-supporting jack, a buffing-pad provided with a substantially flat working surface, means for rotating the pad, and connected mechanism acting automatically to relatively actuate the pad and jack to transfer the point of contact of the pad over the sole of a shoe supported upon the jack, and to change the relative lateral inclination of the pad and jack, substantially as described. 80

7. A buffing-machine, having, in combination, a shoe-supporting jack, a buffing-pad provided with a substantially flat working surface, means for rotating the pad, and connected mechanism acting automatically to relatively actuate the pad and jack to transfer the point of contact of the pad over the sole of a shoe supported upon the jack and to change the relative longitudinal inclination of the pad and jack, substantially as described. 90

8. A buffing-machine, having, in combination, a shoe-supporting jack, a buffing-pad provided with a substantially flat working surface, means for rotating the pad, and connected mechanism acting automatically to relatively actuate the pad and jack to transfer the point of contact of the pad over the sole of a shoe supported upon the jack and to change the relative lateral and longitudinal inclination of the pad and jack, substantially as described. 100

9. A buffing-machine, having, in combination, a shoe-supporting jack, a rotary buffing-pad provided with a substantially flat working surface, mechanism for moving the jack back and forth beneath the pad, and means for adjusting such mechanism to cause the breast of the heel of the shoe supported upon the jack to be brought into close proximity to the buffing-pad at the limit of the movement of the jack in one direction, substantially as described. 115

10. A buffing-machine, having, in combination, a shoe-supporting jack, a rotary buffing-pad provided with a substantially flat working surface, mechanism for relatively actuating the pad and jack to transfer the point of contact of the pad over the sole of a shoe supported upon the jack, and means for thereafter raising the pad above the level of the sole, substantially as described. 120

11. A machine for operating upon the soles of shoes, having, in combination, a shoe-supporting jack, a device for operating upon the sole of a shoe supported upon the jack, jack-
5 actuating mechanism for moving the jack back and forth beneath said device, said jack being movable from a position of presentation to a position in which the sole of a shoe sup-
10 ported thereon is beneath said device, and
15 means for connecting the jack to its actuating mechanism when in the latter position, substantially as described.

12. A machine for operating upon the soles of shoes, having, in combination, a shoe-supporting jack, a device for operating upon the sole of a shoe supported upon the jack, jack-
15 actuating mechanism for moving the jack back and forth beneath said device, said jack being movable from a position of presentation to a position in which the sole of a shoe sup-
20 ported thereon is beneath said device, means for holding said device above the level of the sole during such movement, and means for connecting the jack to its actuating mech-
25 anism when in the latter position, substantially as described.

13. A machine for operating upon the soles of shoes, having, in combination, a shoe-supporting jack, a device for operating upon the sole of a shoe supported upon the jack, jack-
30 actuating mechanism for moving the jack back and forth beneath said device, said jack being movable from a position of presentation to a position in which the sole of a shoe sup-
35 ported thereon is beneath said device, means for connecting the jack to its actuating mech-
40 anism when in the latter position, and means acting automatically to disconnect the jack from its actuating mechanism when in a po-
45 sition in which the toe portion of the sole is in proximity to said device, substantially as described.

14. A machine for operating upon the soles of shoes, having, in combination, a shoe-supporting jack, a device for operating upon the sole of a shoe supported upon the jack, jack-
45 actuating mechanism for moving the jack back and forth beneath said device, said jack being movable from a position of presentation to a position in which the sole of a shoe sup-
50 ported thereon is beneath said device, means for connecting the jack to its actuating mech-
55 anism when in the latter position, and means for adjusting the jack when so connected to change its longitudinal position with relation to said device, substantially as described.

15. A machine for operating upon the soles of shoes, having, in combination, a shoe-supporting jack, a device for operating upon the sole of a shoe supported upon the jack, jack-
60 actuating mechanism for moving the jack back and forth beneath said device, said jack being movable from a position of presentation to a position in which the sole of a shoe sup-
65 ported thereon is beneath said device,

means for connecting the jack to its actuating mechanism when in the latter position, and means for adjusting the jack-actuating mechanism to simultaneously change the longitudinal position of the jack with relation 70 to said device and the extent of the movements imparted to the jack, substantially as described.

16. A buffing-machine, having, in combination, a shoe-supporting jack, a rotary buffing-pad provided with a substantially flat working surface, and connected mechanism acting automatically to move the jack back and forth beneath the pad and to tip the pad laterally and longitudinally, substantially as 80 described.

17. A buffing-machine, having, in combination, a shoe-supporting jack, a buffing device, means for actuating the buffing device, and connected mechanism acting automatically 85 to relatively actuate the buffing device and jack to transfer the point of contact of the buffing device over the sole of a shoe supported upon the jack and to tip the buffing device laterally, substantially as described. 90

18. A buffing-machine, having, in combination, a shoe-supporting jack, a buffing-pad provided with a substantially flat working surface, means for rotating the pad, and connected mechanism acting automatically to 95 relatively actuate the jack and pad to transfer the point of contact of the pad over the sole of a shoe supported upon the jack and to tip the pad laterally, substantially as described. 100

19. A buffing-machine, having, in combination, a shoe-supporting jack, a buffing-pad provided with a substantially flat working surface, means for rotating the pad, and connected mechanism acting automatically to 105 relatively actuate the jack and pad to transfer the point of contact of the pad over the sole of a shoe supported upon the jack and to tip the pad longitudinally, substantially as described. 110

20. A buffing-machine, having, in combination, a shoe-supporting jack, a buffing device, means for actuating the buffing device, mechanism for relatively actuating the buffing device and jack to transfer the point of contact of the buffing device back and forth over the sole of a shoe supported upon the jack, and means for changing the relative lateral inclination of the buffing device and jack while the point of contact of the buffing device is being transferred back and forth over the sole of the shoe, substantially as described. 115 120

In testimony whereof we affix our signatures in presence of two witnesses.
